UNITED STATES PATENT OFFICE.

FRANK HOROVITZ, OF NEW YORK, N. Y.

COMBINED TABLE AND CHECKER-BOARD.

SPECIFICATION forming part of Letters Patent No. 577,984, dated March 2, 1897.

Application filed January 22, 1896. Serial No. 576,380. (No model.)

To all whom it may concern:

Be it known that I, FRANK HOROVITZ, a citizen of the United States, and a resident of New York, in the county of New York and State of New York, have invented certain new and useful Improvements in a Combined Table and Checker-Board, of which the following is a specification, reference being had to the accompanying drawings, forming a part thereof, in which similar letters of reference indicate corresponding parts.

The object of this invention is to provide a combined table and checker or chess board, a further object being to provide a device of this class which may be employed as a checker or chess board at any time, or which may be used as an ordinary table, and which is provided with a sliding drawer or drawers in which checkers or chessmen may be placed and which are also adapted to retain the counters and other and similar articles; and with these and other objects in view the invention consists in the device hereinafter described and claimed.

The invention is fully disclosed in the following specification, of which the accompanying drawings form a part, in which—

Figure 1 is a plan view of my improved combination-table and checker and chess board, showing also the drawer with which the same is provided partially withdrawn; Fig. 2, a side view thereof, and Fig. 3 a transverse section of the upper part of a table.

In the practice of my invention I provide a table A, which is preferably rectangular in form and also preferably square, and said table is supported by means of legs B, but two of which are shown, and beneath the table A is placed a sliding drawer D, which is preferably provided with an inner compartment d and two outer compartments d² and d³, which are shown in dotted lines in Figs. 1 and 2, and these outer compartments d² and d³ are provided with a cover d⁴, and formed in the side of one of said compartments d² is a pivoted door d⁷, and this compartment is adapted to serve as a safe to contain money or other articles of value, and the door d⁷ may be provided with a lock or operated in any desired

manner. The other compartment d³ is provided in practice with a music-box of any desired form or construction. The drawer D is provided with projecting knobs d⁵ d⁶ to serve as handles therefor. I also form in the table A an opening G, which is preferably square in form and in which is pivoted a board H, which is exactly of the same form and size, and said board is pivoted in said opening at the opposite sides thereof by means of pins h, on which it is free to revolve on said pivots.

The surface of the table G is divided into blocks in the manner of a checker or chess board, and the drawer D, as hereinbefore stated, is adapted to receive the checkers or chessmen, and the operation will be readily understood from the foregoing description when taken in connection with the accompanying drawings. The door d⁷ in the side of the drawer D or the compartments d² thereof may be provided with a lock, if desired, and this compartment d² will, as will be apparent, serve as a receptacle for the checkers, chessmen, cards, or any other articles, and it will also be apparent that the board G may be used for other purposes than for a checker and chess board, and other games may be played thereon.

Having fully described my invention, I claim as new and desire to secure by Letters Patent—

1. The combination with a table, in the top of which is formed a rectangular opening, and a game-board of the same size and form as the said opening the surface of said board being designed to represent a checker-board, chess-board, or other game-board, of a sliding drawer, which is provided with a number of compartments, two of which are covered and one of which is provided with a door in the side thereof, substantially as shown and described.

2. The combination with a table, in the top of which is formed an opening, and a game-board of the same size and form pivoted in said opening said board being designed to represent a checker-board, chess-board or other game-board, of a sliding drawer, which is provided with a number of compartments,

two of which are covered, and one of which is provided with a door or doors in the sides thereof, and another compartment which is designed to receive a music-box, substantially as shown and described.

5 In testimony that I claim the foregoing as my invention I have signed my name, in pres-

ence of the subscribing witnesses, this 20th day of January, 1896.

FRANK HOROVITZ.
